United States Patent

Des. 236,154

Patented July 29, 1975

236,154

BOOKBINDING MACHINE

Henry N. Staats, Deerfield, Robert S. Quandt, Lincolnshire, and Viktor Struch, Skokie, Ill., assignors to General Binding Corporation, Northbrook, Ill.

Filed Nov. 30, 1973, Ser. No. 420,689

Term of patent 14 years

Int. Cl. D15—99

U.S. Cl. D55—1

Fig. 2

FIG. 1 is a perspective view of a bookbinding machine showing our new design;

FIG. 2 is a rear perspective view thereof;

FIG. 3 is a left side elevational view;

FIG. 4 is a top plan view; and

FIG. 5 is a bottom plan view.

In FIGS. 2-5 the power cord is shown only fragmentarily for convenience of illustration.

We claim:

The ornamental design for a bookbinding machine, as shown and described.
